FRANK B. STEARNS, OF CLEVELAND, OHIO.

SELF-IGNITING ENGINE.

Application filed May 29, 1924, Serial No. 716,563. Renewed December 20, 1926.

This invention relates to internal combustion engines, and more particularly to the type known as self-igniting.

One of the objects of my invention is to increase the efficiency and power produced by such an engine, by providing a structure whereby compressed air can be introduced into the cylinder in such volume and at a speed sufficient to completely displace the exhaust gases after each explosion, and to fill the cylinder with a fresh supply of compressed air which is further compressed by the compression stroke of the piston to ignite the fuel charge.

Another object of my invention resides in providing mechanism whereby the time at which fuel is injected into the cylinder can be manually regulated.

Another object of my invention is to provide mechanism which can be normally regulated to control the volume of fuel which is injected into the cylinder during each injection period, such regulation, of the quantity of fuel injected, ranging from full capacity of the injection ports to as small a quantity as is desired.

These and other objects and the invention itself will be more apparent from the following detailed description.

In the accompanying drawings,—

Fig. 1 is a side elevation of an engine embodying my invention;

Fig. 2 is a top plan view of the same, the air compression being partially broken away;

Fig. 3 is an elevation of another side of the engine;

Fig. 4 is a vertical sectional view of the engine taken on line 4—4 of Fig. 2;

Fig. 5 is a fragmentary elevation of another side of the engine showing the eccentric shaft and the mechanism operated thereby;

Fig. 6 is a fragmentary section of a portion of the fuel valve operating mechanism;

Fig. 7 is an end elevation of the mechanism for adjusting the turning of the fuel valve operating mechanism;

Fig. 8 is a top plan view of the cylinder head;

Fig. 9 is a sectional view of the same taken on line 9—9 of Fig. 8;

Fig. 10 is a side elevation of the same;

Fig. 11 is another side elevation of the same;

Fig. 12 is a perspective view of the head shown partially in section; and

Fig. 13 is a fragmentary vertical section of

the fuel nozzle with the valve element seated therein.

Fig. 14 is a longitudinal, medial, sectional view of a form of compressor which may be employed co-operatively as a part of the mechanism of my invention, the crankshaft illustrated in Fig. 14 being the same crankshaft illustrated in Fig. 4 as broken off at the left side of the drawing, the broken-off portion in Fig. 14 joining with the broken-off portion of Fig. 4.

Referring now to the drawings by characters of reference, 15 illustrates a crank case having a crank shaft 16 mounted in bearings 60 therein. A cylinder 17 is secured upon the crank case and is in open communication with the interior thereof. A piston 18 is mounted to reciprocate in the cylinder and is provided with a wrist pin 19 to which the piston rod 20 70 is connected, the other end of the rod being connected to the crank shaft. The cylinder is provided with a pair of oppositely disposed exhaust ports 21 arranged so that they are opened by the piston when in its lower position. The parts of the engine, so far described, are a conventional design of the two-cycle type, and a further description of these parts is therefore not thought to be necessary.

An air compressor 22 is secured upon the 85 crank case and is provided with a pair of outlet pipes 23 which are arranged to convey the compressed air to the cylinder head 24, a cam shaft, or eccentric shaft 25 is carried by bearings 26 secured upon the crank 90 case, and a gear 27 is secured thereto. This gear is driven by the chain 28 which extends around the gear 29 secured to the crank shaft. A shaft 30 extends eccentrically from one end of the cam shaft and a compressor operating 95 rod 31 is adapted to be reciprocated thereby. The compressor illustrated herein is the subject matter of my pending application, Serial No. 715,538, filed May 24, 1924, to which reference may be had for the details and operation of the parts not shown herein.

A compressor cylinder 131 is secured upon the top of the crank case in open communication with the interior thereof and adjacent the engine cylinder, and a piston 132 having 105 an annular reduced end portion is mounted to reciprocate therein. A pin 133 is carried by the piston, and a rod 134 is connected to such pin and the crankshaft 26. The cylinder is provided with a plurality of spaced 110 air inlet ports 135 arranged in the same flange around the upper end thereof, and outlet

ports 136 are provided in the cylinder wall intermediate the inlet ports and the end of the cylinder. The pipes 23 are secured to the compressor cylinder and provide passages 5 for conducting the compressed air from the outlet ports to the engine head.

The compressor cylinder is provided with a closure head 137 which is secured upon the upper end thereof by bolts 138, and an apertured hub 139 extends centrally therefrom into the cylinder. The inner end of the hub terminates in an interiorly extending flange 140 formed to provide a bearing through which a stem 141 is slidably mounted. 10 A hollow packing nut 142 is threaded into the upper end of the apertured hub portion of the head and provides a bearing for the stem 141 which extends therethrough. A stationary hollow valve element 15 is mounted within the upper end of the compressor cylinder and is positioned in opposed relation to the reciprocating piston 132. The stationary valve element consists of an annular head 143 of smaller diameter 20 than the cylinder, having a skirt portion 144 extending therefrom terminating in an outwardly extending flange 145 of an outside diameter substantially that of the bore of the cylinder. The flanged portion of the 25 skirt is secured against the cylinder head by screws 146. The skirt 144 of the stationary valve element, including the flanged end, is provided with equally spaced slots 147 which extend lengthwise thereof and terminate adjacent the portion head. An expanding annular ring 148 is mounted in an annular groove in the side wall of the skirt, below the 30 ends of the slots. The inner end of the stem is threaded, and a valve supporting plate, a spider 150, is screwed thereon. This plate is provided with a central internally threaded hollow hub portion 151, and also with arms 152 which extend radially from the periphery thereof. The arms are arranged so 35 that they will extend through the slots in the skirt portion of the valve element and are provided adjacent their outer ends with bolt holes 153. A slidable cylindrical valve element 154 is positioned within the compressor cylinder, beneath the spider, and is secured against the under side of the arms by bolts 155, which project through the holes 153. The cylindrical movable valve is formed of a diameter to slidably engage the inner wall of 40 the cylinder, and an expanding ring 156 is positioned in an annular recess 157 formed in the outer wall of this valve element. The inner wall of the cylindrical valve element is provided with a plurality of slots 158 which 45 extend lengthwise thereof and terminate adjacent the lower end of the skirt.

The valve element 154 which is secured to the arbor is of such thickness that it will engage the skirt 144 of the stationary valve element and the inner wall of the cylinder. 50

The valve element 154 is vertically reciprocated by the movement of the stem 141 to which the spider is secured. The arrangement of the movable valve element is such that it will cover the air inlet ports in the cylinder wall when in its lower position, and when in such position the lower ends of the slots 158 will lie beneath the head of the stationary valve element, whereby establishing communication between the compression chamber beneath the head of the stationary valve element, and the outlet ports 136. Upward movement of the movable valve element first covers the slots 158 beneath the skirt of the stationary valve element and then uncovers the inlet ports 135. The slots 147 through which the spider arms extend, permit the spider to be reciprocated a limited distance, thereby reciprocating the movable valve element between the cylinder wall and the skirt beneath the cylinder head. The expanding rings 156 and 148 will engage respectively the cylinder wall and the inner wall of the movable valve member thereby providing a sealing which materially increases the compression of air within the compression chamber and prevents leakage from the conduits into compression chamber. 80

The compression chamber is formed within the cylinder, intermediate the head of the stationary valve element and the movable piston. The reduced end of the piston will project within the annular movable valve element, when approaching its extreme upward travel and will extend in close proximity to the head of the stationary valve element when in its extreme upper position, thereby displacing substantially the entire volume of compressed fluid from the compression chamber. 100

The mechanisms for operating the movable compressor piston and the movable valve element are so arranged, and operated, that as the compressor piston starts down, the inlet ports are uncovered by the movable annular valve element, and they remain uncovered until the compression piston is at the bottom of its travel. A fresh supply of air passes into the compression chamber through the ports when uncovered. As the compressor piston starts its upward travel, the inlet ports will be closed by the annular valve element and, as the annular valve element moves down the slots in the inner wall thereof, will extend below the head of the stationary valve element, permitting the compressed air to pass through passages formed by the slots and the skirt of the stationary valve element, into the upper portion of the cylinder and the pipes 121. 110

It will be observed that the valve elements control both the passages of air into the cylinder, and the passage of compressed air from the compression chamber. 115

The cylinder head 24 is formed with a 120

125

central aperture 32 which extends axially therethrough and receives the fuel feeding device. A pair of conduits 33 extend through the head and are arranged so that compressed air can be directed thereby downwardly into the cylinder. The conduits extend inwardly, from opposite sides of the head, in a horizontal plane and are offset with respect to each other so that they extend on opposite sides of the aperture 32. The horizontal portion of the conduits terminate adjacent the aperture 32 and curve downwardly, extending through the head so that they open through the inner wall thereof. The ends of the conduits extending axially of the head, converge toward the outlet ends thereof and lie adjacent the aperture 32 and on opposite sides thereof. The sides of the head adjacent the conduits are provided with flanges 34 to which the pipes 23 from the compressor are secured by bolts 35, establishing communication between the conduits and the compressor. It will be observed that the conduits feed the compressed air downwardly into the cylinder, and that they are of large area so that a large volume of compressed air can pass into the cylinder after each explosion therein. The head is provided with peripheral apertures 13 through which studs extend to secure the head upon the cylinder. Suitable passages 36 are provided within the head, so that a cooling agent may circulate therethrough in the conventional manner. Guides 37 extend axially into the downwardly extending portion of the conduits and removable guides 38 are inserted therein. Valves 39 are arranged to seat against the wall adjacent the outlet ends of the conduits in the head, and stems 40 extend therefrom through the guides 38. Retainers 41 are secured adjacent the upper end of the stems and coil springs 42, encircling the valve stems bear against the retainers at one end and against the engine head at their other end. The springs are provided to normally maintain the valves 39 in position to close the conduits, so that compressed air will pass into the cylinder only while the valves are mechanically unseated.

A cam 44 is secured to the eccentric shaft 25 adjacent one side of the cylinder for actuating the valve operating mechanism. Bearings 45 extend from the cylinder and are provided with vertically extending apertures in alignment with the cam. A rod 46 extends through the bearings 45 and is provided at its lower end with a plate 47 which the cam engages to move the rod upwardly. A pair of levers 48 are pivotally connected at one end to the upper end of the rod, and are adapted to be actuated by the movement thereof. Parallel shafts 49 are rotatably mounted in brackets 50 which are secured upon the engine head, and rocker arms 51 are secured to one end of these shafts and are adapted to be

actuated by the levers 48, the rocker arms having recesses 52 provided in the under sides thereof within which the ends of the levers 48 engage. Rocker arms 53 are secured to the shafts 49 and are provided with bifurcated ends 54, which carry rollers 55. The rocker arms 53 are arranged so that the rollers carried thereby will engage the end of the valve stems 40, moving them downwardly when the shafts 49 are rotated by the cam operated mechanism. It will be seen that the cam can be placed upon the eccentric shaft to move the valve operating mechanism at the time desired, relative to the other operating parts of the engine, and the cam is designed to retain the mechanism in an upward position sufficient length of time to maintain the valves in open position long enough so that enough compressed air passes into the cylinder from the conduits to completely scavange the burnt gases while the exhaust ports are open, and to fill the cylinder with compressed air when the exhaust ports are again closed.

A fuel injector head 56 is secured upon the cylinder head and is provided with a hub portion extending centrally from each face thereof. The injector head is provided with a fuel feeding passage 57 which extends horizontally through one side thereof, and within which a fuel supply pipe 58 is secured. A fuel pump 59 of any conventional design is secured upon the crank case adjacent to the cylinder by brackets 89, and is arranged to cause fuel under pressure to pass through the pipe 58 and into the passage 57 in the injector head. A pump shaft 60 is rotatably mounted in bearings 61 extending upwards from the crank case, this shaft being parallel with the eccentric shaft and located on the opposite side of the engine cylinder therefrom. A gear 62 is secured to the pump shaft and is driven by a chain 63 which extends around a gear 64 secured to the eccentric shaft. A pump rod 65 is secured to the pump shaft and is reciprocated thereby. A pipe 66 leads from a source of fuel supply and is connected with the pump.

The lower hub portion 67 of the injector head is formed to extend into the aperture 32 in the engine head and its lower end is of reduced diameter and threaded externally. An aperture 68 extends axially through the injector head and the hubs which extend therefrom. The lower end of the aperture 68 is enlarged and receives an end of the fuel feeding device 69 which is inserted therein. The fuel feeding device is in the form of a nozzle and a flange 70 extends therefrom, being held against the end of the hub by a cap 71 which is screwed upon the threaded end of the hub. The nozzle extends through the opening 32 in the head and projects into the explosion chamber beneath the head, being provided with fuel outlet ports 72 for spraying fuel into the cylinder. The aper-

ture 68 is enlarged just above the nozzle so that its diameter is slightly more than the diameter needle valve. A passage 73 extends downward in the injector head and connects the aperture 68 just above the nozzle with the passage 57, so that the interior of the nozzle will be in open communication with the fuel pump.

A hollow sleeve 75 is screwed upon the upper hub 76 of the injector head, and an apertured bearing 77 is screwed into the upper end of the sleeve. A cap bearing 78 is screwed upon the upper end of the hub 76, and a valve closure element extends through the bearings and the aperture in the hubs. The lower end of the valve is conically formed so that it will extend into the nozzle and seat against the conical shoulder 120 when in its lower position to close the outlet ports 72, and is of less diameter than the interior of the nozzle so that fuel can pass through the nozzle while it extends therein. A retainer 79 is secured to the valve element, and a coil spring 80 extends around the valve element, bearing against the retainer and the underside of the bearing 77. This spring will normally press the valve downwardly so that it closes the seat in the nozzle, to prevent passage of fuel into the cylinder. The upper end of the valve element is threaded and nuts 81 are screwed thereupon. It will be seen that the distance the conical portion of the valve element is moved from the seat 120 will determine the volume of fuel permitted to be sprayed with the cylinder.

The upper end of the sleeve 75 is provided with an outwardly extending flange 82 having a bifurcated bracket portion 83 extending upwardly therefrom. A plurality of studs 84 are screwed into the flange 82 and are arranged to provide supporting standards for a support 85. The studs are threaded into the support and nuts 86 are provided for the studs to maintain the support thereon. The support is provided with a threaded passage which is in vertical alignment with the valve element, and a threaded rod 87 for regulating the distance the valve can be raised, is adapted to be screwed through the passage in the support. A handle 14 extends through the outer end of the rod 87 so that it can be manually operated to regulate the position thereof. It will be seen that the regulating element can be screwed toward the valve so that it will engage the end thereof when the valve is in its lowest position closing the ports in the nozzle, and also that the element can be adjusted to permit the valve to be raised from the seat any distance desired between the closed position and the fully open position. The regulating element can in this manner be adjusted to control opening movement of the valve and the volume of fuel which is permitted to pass into the cylinder

through the nozzle ports will be regulated thereby.

Mechanism is operated by the eccentric shaft for lifting the valve and includes a rocker arm 90 which is pivoted intermediate its ends and pivotally mounted in the bifurcated portion of the bracket 83. The rocker arm is arranged so that one end 91 thereof, which is bifurcated, will engage one of the nuts 81 which is screwed upon the valve member. Rocking of this arm will lift the valve from its seat, where it is normally retained by the spring 80, a full movement thereof, or the length of movement permitted by the element 87 if adjusted to limit the movement of the valve. A rod 92 extends through and is 80 slidable in a sleeve 93, which extends into an aperture in the end 94 of the rocker arm. The end of the rod is threaded and a retainer 95 is screwed thereon, being secured in desired position by lock nuts 96. A coil spring 97 85 surrounds the rod, and bears against the upper end of the sleeve 93. The retainer is positioned to create sufficient tension upon the spring, so that it will operate the rocker arm with the rod. It will be seen, however, that 90 when the movement of the valve and the rocker arm is limited, so that they will not move their normal distance, that the spring 97 will permit the rod to continue its entire movement without affecting the rocker arm. 95

The lower end of the rod 92 is pivotally connected by a connector to one end of a link 98 which link is arranged to underlie the eccentric shaft. The other end of this link is pivotally secured within the bifurcated 100 end of a rocker arm 99 secured to shaft 100 which is rotatably mounted in a pair of brackets 101 secured to the crank case. A handle 102 is secured at one end to the shaft 100 and when moved back and forth will rotate the shaft, thereby changing the normal position of the link 98. A roller 103 is carried by the link 98 and is adapted to be engaged by a cam 104 secured to the eccentric shaft. As this cam rotates it strikes the 110 roller secured to the link, moving the floating end of the link downwardly and thereby moving the rod 92 therewith.

The relation of the link 97 to the operating cam is regulated by the hand lever, so that 115 the time at which the cam strikes the roller can be regulated so that it can be advanced or retarded, thereby actuating the fuel valve correspondingly.

A curved sector 105 extends from the engine cylinder and bolts 106 are secured to the hand lever 102, so that the sector will extend therebetween. A plate 107 extends across the end of the bolts and provides a support for a stud 108. By screwing the stud so that it engages the sector the lever can be maintained stationary. This mechanism serves to permit the handle to be adjusted to change the 120 125

timing of the fuel injection and also secures the handle to maintain the timing in the desired relation.

It will be seen that I have provided mechanism for regulating the timing of the fuel injection and for controlling the volume of fuel injected when the fuel valve is operated, both of such mechanisms being adjustable while the engine is operating or while it is not in operation. I have also provided an engine in which compressed air can be introduced after each explosion to completely scavange the cylinder of burnt gases and to completely charge the cylinder with a full volume of compressed air at the beginning of the compression stroke of the piston. The various mechanisms are all driven from an eccentric shaft and can be regulated to be operated in the succession desired.

20 Various changes can be made in the embodiment described without departing from the spirit of my invention and the scope of the appended claims.

1. In an internal combustion engine, the combination with an engine cylinder of a compressor for supplying air to the engine cylinder said compressor comprising a cylinder and a piston reciprocable therein, of a pair of inlet ports in the head of the engine cylinder and a plurality of exhaust ports in a lateral wall of the engine cylinder, of a piston disposed within the engine cylinder and reciprocable therein, said piston adapted to uncover the exhaust ports to permit the egress of burned gases from the engine cylinder when the piston is in down-stroke position, a conduit adapted to communicate air from the compressor to the engine cylinder through the said inlet ports, a compressor valve at the compressor end of the conduit and adapted to control the communication of air under pressure between the conduit and the compressor, said compressor and said inlet valves when closed adapted to trap air under pressure in the conduit, means for operating the inlet valve to effect a supply of air from the conduit to the engine cylinder after the exhaust port therefor has been uncovered by the downward movement of the piston, said compressor valve adapted to effect a flow of air from the compressor cylinder to the conduit to supercharge the engine cylinder when the exhaust ports therefor are recovered by the engine piston during its consequent upward movement, said inlet valve operating means adapted to reclose the inlet valve to discontinue the supercharging of the engine after a length of time following reclosure of the engine exhaust port, and a fuel injection valve disposed in the head of the cylinder for periodically injecting atomized liquid fuel, and crank shaft means for reciprocating the engine and compressor pistons in their respective cylinders synchronously, said crank shaft means adapt-

ed to effect corresponding strokes of the one piston ahead of those of the other.

2. In an internal combustion engine, the combination with an engine cylinder, a piston reciprocable therein, a cylinder head, an inlet port in the cylinder head, an exhaust port through the side walls of the cylinder and adapted to be uncovered by the piston when the piston is approaching the bottom of its stroke, to permit the egress of burned gases from the cylinder, a compressor comprising a relatively telescopicable piston and cylinder for supplying air under pressure for the engine cylinder, of a conduit interconnecting the said source and the engine cylinder through the said inlet valve, of an air supply cut-off valve disposed at the inlet end of the said conduit and operable to communicate air to the conduit after the reclosure of the exhaust port of the engine cylinder by the piston when travelling on its upward stroke, and means adapted to actuate said inlet valve to permit flow of compressed air from the conduit starting at a predetermined length of time after uncovering of the exhaust port, and a fuel injection valve disposed in the head of the cylinder for periodically injecting atomized liquid fuel, the compressive stroke of the engine piston adapted to be completed subsequently to that of the pump piston, said pump piston stroke completed after the closing of said inlet valve.

3. In a two-cycle engine, the combination with a cylinder, of a reciprocable piston in the cylinder, of inlet and exhaust ports therefor, said exhaust port being disposed more remote from the head of the cylinder than the inlet port, an inlet valve for the inlet port and means adapted to operate the said inlet valve synchronously with the movement of the piston in the cylinder and adapted to open the inlet valve only after the exhaust port has been opened, means to supply air under pressure to the cylinder, a conduit interconnecting the said means and the cylinder through the said inlet port, a control valve at the inlet end of the said conduit for limiting the periods of charging of the conduit with the compressed air from the source, said control valve operating means being operable synchronously with the piston in the cylinder, whereby air may be supplied, first, from compressed air trapped in the conduit by the said inlet and control valves, and, subsequently, by air communicated to the engine through the conduit from the source, and a fuel injection valve disposed in the head of the cylinder for periodically injecting atomized liquid fuel, said air supplying means comprising a cylinder and piston reciprocable therein and driving means adapted to reciprocate the piston by motion communicated from the engine piston, said driving means adapted to effect compression strokes of the engine piston subsequently to the strokes of the other piston.

4. In an internal combustion engine, the combination with an engine cylinder of a piston disposed within the cylinder and reciprocable therein, a pair of inlet ports in the head of the cylinder and a plurality of exhaust ports in a lateral wall of the cylinder, means adapted to open said exhaust ports to permit the egress of burned gases from the cylinder when the piston is in exhaust-stroke position, 10 a compressor comprising a reciprocating air compressing piston and a cylinder therefor, a conduit adapted to communicate air from the compressor, in pulses, towards and into the engine cylinder through said inlet valves, a 15 compressor valve at the compressor end of the conduit, said compressor valve and said inlet valves when closed adapted to trap air under pressure in the conduit, means for operating the inlet valve to effect a supply of 20 air from the conduit to the engine cylinder after the exhaust port therefor has been uncovered by the downward movement of the piston, means to operate said compressor valve to effect a flow of air from the compressor cylinder to the conduit to supercharge the engine cylinder when the exhaust ports therefor are 25 recovered by the engine piston during its consequent upward movement, said inlet valve operating means adapted to reclose the inlet 30 valve to discontinue the supercharging of the engine at the end of a predetermined period following reclosure of the engine exhaust port, a fuel injection valve disposed in the head of the cylinder for periodically injecting 35 atomized liquid fuel and means to effect closure of the inlet valves during the compression stroke of the air compressing piston and to effect closure of the compressor valve at approximately the end of the pump stroke.
- 40 5. The method of economically supplying air to an engine cylinder comprising the synchronous reciprocation of engine cylinder and air compressor cylinder pistons, the compressor cylinder piston being moved on its compression and expansion strokes ahead of the corresponding strokes of the engine piston, compressing air in the compressor during the compression period thereof, communicating meanwhile the compressed air to a connecting 45 conduit leading to the engine cylinder, shutting off the conduit at its approach and from the compressor cylinder and at its exhaust end from the engine cylinder, firing a charge including previously compressed air and fuel 50 in the engine cylinder, then exhausting the products of combustion from the engine cylinder after the engine piston has moved nearly to the end of its exhaust stroke, then when the pressure in the engine cylinder approaches 55 minimum pressure, admitting air from the connecting conduit to the engine cylinder, while the compression cylinder is shut off from the connecting conduit, the compressor piston meanwhile reaching the end of its expansion stroke and then subsequently start- 60

ing on its compression stroke, then effecting communication of the air in the compressor cylinder to that in the connecting conduit when the increasing pressure of air in the compressor cylinder approximates that of the 70 pressure at the time in the compressor cylinder, subsequently discontinuing the exhaust of burned gases from the engine cylinder when the newly admitted air starts to flow therefrom, then discontinuing the admission 75 of air to the engine cylinder, while the compression of air by the compressor continues, then discontinuing the communication of compressed air to the interconnecting conduit when the pressure in the interconnecting 80 conduit reaches a maximum pressure, and repeating the above cycle periodically.

6. The method of economically supplying air to an engine cylinder, comprising the compressing of air, confining the compressed air 85 contiguously to the cylinder while firing the charge of previously compressed air and fuel contained in the engine cylinder, then initiating the exhausting of the products of combustion from the engine cylinder after the engine piston has moved nearly to the end of its exhaust stroke, the when the pressure in the engine cylinder, resulting from the exhausting, approaches minimum pressure, supplying 90 air from the said contiguous supply of compressed air to the engine cylinder, then initiating the replenishment of contiguously confined compressed air while continuing the supply of air to the engine cylinder, subsequently 95 discontinuing the exhaustion of the products of combustion from the engine cylinder when the newly supplied air following the products of combustion starts to flow therefrom, then discontinuing the supply of air to the engine cylinder while continuing the compressive 100 confinement of additional air, then subsequently discontinuing the compression, and effecting confinement of air, and repeating the 105 above cycle, periodically.

7. The method of periodically supplying 110 air to an engine cylinder, comprising the periodic communication of air to the cylinder from a source of air confined under pressure contiguous to the cylinder during a certain 115 part of the engine cycle comprising the latter part of the exhaustion part of the cycle, and the subsequently occurring supercharging part of the cycle, replenishing the confined compressed air only during another portion 120 of the engine cycle, comprising a part of the supercharging portion of the cycle, and the part of the subsequent engine cycle portion immediately following, discontinuing meanwhile the supply of air to the engine cylinder during the last named subsequent portion of 125 the engine cycle.

In testimony whereof I hereunto affix my signature this 26th day of May, 1924.
